CLAIM

The ornamental design for a tail band sensor, as shown and described.

DESCRIPTION

Tail band sensor

2.1: Top, front, left perspective view in a closed configuration

2.2: Top, back, left perspective view, thereof

2.3: Top plan view, thereof

2.4: Bottom plan view, thereof

2.5: Left side elevation view, thereof

2.6: Right side elevation view, thereof

2.7: Front elevation view, thereof

2.8: Back elevation view, thereof

2.9: Top, front, left perspective view in an open configuration

2.10: Top, back, left perspective view, thereof.

Reproductions 2.1 and 2.2 are perspective views in the closed positions; reproductions 2.9 and 2.10 are perspective views in the open positions.

The broken lines shown in the drawings illustrate portions of the tail band sensor that form no part of the claimed design.

1 Claim, 6 Drawing Sheets(56)
